MEANS FOR SEPARATING ADHERING ROLLED METAL SHEETS

Filed Sept. 6, 1927

UNITED STATES PATENT OFFICE

1,923,264

MEANS FOR SEPARATING ADHERING
ROLLED METAL SHEETS

Eugen Hinderer, Hamborn, Germany, assignor
to Vereinigte Stahlwerke Aktiengesellschaft,
Dusseldorf, Germany, a Corporation of Ger-
many

Application September 6, 1927, Serial No. 217,847,
and in Germany January 3, 1927

1 Claim. (Cl. 29—17)

Applications have been filed in Germany, Jan-
uary 3, 1927, January 6 1927 and April 25 1927.

This invention relates to improvements in or
modifications of the means for separating ad-
hering rolled metal sheets as described in the
5 specification of my prior U. S. application for
patent Ser. No. 159,735 filed 7th January, 1927,
which has become Patent No. 1,749,075, and es-
sentially consisting in splitting the adhering
10 rolled metal sheets open at their front ends and
pulling the same freely over a cutterlike contri-
vance engaging between them and having a
separating motion during the free travel of the
sheets over the same.

According to the present invention, means are
15 provided for increasing the separating action of
the cutter-like contrivance. To this end, the
latter is moved to and fro in the plane lying be-
tween the sheets to be separated, in a manner
20 depending on the adhering resistance to be
overcome, the thickness and width of the sheets
to be separated, and the strength of the latter.

The cutterlike separating contrivance can, for
instance, be reciprocated in said plane in a di-
rection parallel to the pulling direction of the
25 sheets. Said contrivance is preferably provided
with a sawlike cutting-edge and reciprocated in
said plane in a direction transversely to the pull-
ing direction of the sheets. Or, it can consist
30 of two superposed parts having each a sawlike
cutting-edge and which are reciprocated in said
plane in opposite directions transversely to the
pulling direction of the sheets. In all cases, a
35 compressed-air motor can be coupled directly
with the cutterlike contrivance for driving the
same and imparting thereto a high speed of at
least 200 units of movement per minute, for ob-
viously, the separating action of the cutterlike
40 contrivance is increased with increasing speed
of the same. Furthermore, means are provided
for guiding the cutterlike contrivance during its
rapid reciprocation.

The accompanying drawing illustrates dia-
grammatically by way of example how the in-
vention can be put into practice:

45 Fig. 1 is a side view partly in section, while
Fig. 2 is a fragmentary plan view, of a prac-
tical constructional form of the improved appa-
ratus, and Fig. 3 is a front view of the appa-
ratus.

50 Figs. 4 and 5 are respectively a plan view and
a front view of a modified construction of the
cutterlike contrivance with its guiding and driv-
ing means.

55 Referring to Figs. 1 and 2—The sheets to be
separated are caught by the tongs 2 and pulled

by means of the cords 3, drum 4, toothed-gear-
ing 5, and motor 6, over the cutterlike separat-
ing contrivance 1.

In Fig. 2 it is seen that the cutterlike con-
trivance 1 is provided with a sawlike cutting-
edge, the tongs 2 and pulling cords 3 being shown 60
behind the same. The cutterlike contrivance is
rapidly reciprocated in the plane of cleavage
between the sheets and in a direction transverse-
ly to the pulling direction of the sheets, by means
of the motor 7, bevel-gearing 9, shaft 8 and 65
eccentric 10 with which the cutterlike contriv-
ance is connected.

Figs. 4 and 5 show a two-part cutting device
having a sawlike cutting-edge on each of its
two superposed cutting members 11, 12 which 70
are mounted in lateral guides 13 and in direct
connection with compressed-air motors 14, 15
by which they are rapidly reciprocated or oscil-
lated generally along their axes in the plane of
cleavage between the sheets and in relatively op- 75
posite directions transversely to the pulling di-
rection of the sheets.

What I claim, is:—

Apparatus for separating adhering rolled
sheets including the combination, with means 80
for positively moving a pair of adhering sheets
in a feeding direction, of a pair of superposed
cutting devices provided with sawlike cutting
edges, which cutting devices are disposed trans-
versely between said sheets and individually re- 85
ciprocable while in mutual contact and along
their own longitudinal axes in the cleavage zone
transversely to the direction of movement of
said sheets, and means for individually recipro-
cating said cutting devices in said cleavage zone 90
in opposite directions in order to add a direct
splitting action to the cutting action of said cut-
ting devices while generally maintaining the
normal flat shape of said sheets as uniformly as
possible during separation thereof. 95

EUGEN HINDERER.
